METHOD OF AND MACHINE FOR BALANCING THE TWIST OF ELASTIC YARN

Fayette D. Chittenden, Providence, and Kenneth J. Rupprecht, Barrington, R. I., assignors to United States Rubber Products, Inc., New York, N. Y., a corporation of Delaware

Application November 20, 1935, Serial No. 50,666

3 Claims. (Cl. 117—26)

This invention relates to a yarn rewinding machine for correcting the twist of an "off-balance" elastic yarn, and to a method of balancing the yarn.

5 Elastic yarn comprising a rubber core having a covering of textile yarn spirally wound thereupon in one direction and a second covering of textile yarn spirally wound thereupon in an opposite direction is manufactured in large quantities. The rubber core is held by the covering yarns in a tensioned condition and as a result the elastic yarn tends to curl and kink under the contractive force of the stretched core unless the oppositely wound spiral covers are so applied 10 that they exert a balanced action upon the core.

It is important that elastic yarn and particularly the finer sizes intended for use in shuttles or knitting machines be balanced when ready for use so that a suspended free length thereof will hang straight and not tend to kink when free 15 from tension, for if the yarn is unbalanced it will not work well in a shuttle or knitting machine.

In covering elastic yarn it is difficult to always 20 secure the desired balanced effect and it has been the practice heretofore when the finished yarn was found to be kinky or unbalanced to correct or reclaim the yarn by removing the excess twist, the direction in which the yarn should 25 be untwisted depending upon the direction in which the yarn is "off-balance".

Heretofore, the unbalanced condition of the 30 yarn was corrected by spooling and then re-spooling it several times by pulling the elastic 35 yarn over the head of the spool. This operation removes one twist from the yarn for each revolution or coil of the yarn about the spool, but the repeated drawing of the yarn off the end of one spool and winding it on another to correct 40 the twist is time consuming.

The present invention therefore contemplates 45 a machine for correcting the twist of off-balance elastic yarn in a single operation instead of a number of winding operations as heretofore, and 50 an important feature of the invention resides in yarn-winding mechanism including a spool-supporting spindle and means for rotating the spindle and spool at a predetermined ratio to the speed at which the yarn is pulled from the spool 55 so as to untwist the yarn just enough to correct its "off-balance" condition.

Another feature resides in a yarn-tensioning pull roll between the spindle-operated spool and means upon which the yarn is wound and which

is operable to deliver the yarn to the latter at substantially a constant tension.

Other features of the invention and novel combination of parts in addition to the above will be hereinafter described in connection with the 5 accompanying drawing which illustrates one good practical form thereof.

In the drawing:—

Fig. 1 is a diagrammatic side elevation of winding mechanism constructed in accordance with 10 the present invention;

Fig. 2 is a front elevation of the mechanism of Fig. 1;

Fig. 3 is a view of a portion of the yarn spool of Fig. 1 showing the kinked elastic yarn extending therefrom, part of the yarn being magnified to show the inner and outer spiral covering; and

Fig. 4 is a view similar to Fig. 3 but shows the rubber core as provided with a single spiral covering.

In order to reclaim unbalanced elastic yarn by correcting its unbalanced condition in accordance with the present invention the "off-balance" 20 yarn is wound on a spool such as 10 so that the 25 yarn may be pulled over the head thereof, and this spool is mounted upon a spindle 11 which is rotatably mounted in supporting means 12.

The elastic yarn 13 has been shown in Fig. 3 as in an unbalanced kinky condition prior to 30 having this condition corrected, and as here shown the elastic or rubber core 14 has spirally wound thereupon an inner cover of yarn 15 and outer cover of yarn 16. The present invention, however, may be employed to correct the unbalanced condition of other types of elastic yarn.

The yarn 13 is drawn from the spool 10 in an axial direction and a fixed guide 17 for the yarn is preferably provided near the upper end of the spool to guide the yarn and cause it to balloon as 40 it leaves the spool, as shown, so as to clear the head of the spool. The yarn 13 is shown as passing from the guide 17 to a second guide 18 positioned below a yarn-tensioning pulley 19 about which the yarn is looped as shown. The yarn 45 passes from the pulley 19 through the fixed guide 20 to a guide 21 of the traversing bar 22, and then about the skein drum 23 which is driven at the desired surface speed by the drive roll 24.

The pulley 19 is preferably driven at a surface speed several times faster than the surface speed of the drum 23 and the slippage of the yarn on the pulley compensates for variations in elongation of the elastic yarn in spooling so that the 55

yarn is delivered to the drum under constant tension.

The spool-supporting spindle 11 may be driven by a belt 25 or otherwise but means should be provided for controlling the speed of this spindle relative to the speed at which the yarn is drawn off the spool 10 by the winding mechanism, so that the present mechanism may be employed to vary the amount of twist that is to be removed 10 from the yarn.

In reclaiming or correcting the twist of elastic yarn in accordance with the present invention the skeins or other packages of "off-balance" yarn may be sorted into batches according to the degree of balance. They are then spooled, that is, wound on spools such as 10 and placed on the spindles 11. The operator then adjusts the spindle to the proper speed for the batch on hand. It is found that the operator after some experience will be able to judge accurately the correct spindle speed for any batch of yarn to be balanced. The yarn when balanced will hang limp when tested.

As the yarn is drawn over the end of the spool 10 by the rotation of the drum 23 one twist will be removed from the yarn 13 for each revolution of the spindle plus one turn for each wrap of yarn upon the spool, and as a result any desired number of twists can be removed from the yarn 30 in a single unwinding operation.

In Fig. 4 is shown a different type of elastic yarn comprising a rubber core 26 having spirally wound thereupon a single covering of yarn 27. It is apparent that if the covering 27 is wound 35 upon an untwisted core 26 the elastic yarn thus produced will be badly out of balance and will tend to kink as shown in Fig. 4. This condition, however, may be readily corrected upon the machine of Fig. 1 by so operating this machine that 40 it will twist the core 26 and decrease the twist of the covering yarn 27 sufficiently to produce a balanced elastic yarn having a single spiral covering, the core being twisted in one direction and the covering in the opposite direction in the balanced yarn.

While the elastic yarn to be balanced is herein shown as wound upon a spool 10 it will be understood that it may be wound upon other types of packages to be drawn endwise therefrom, and that other forms of means than herein shown 5 may be employed to rotate the spool or package at the proper speed during the unwinding operation, the important feature of both the method and apparatus being the rotation of the package at the proper speed as the yarn is drawn 10 therefrom.

Having thus described our invention what we claim and desire to protect by Letters Patent is:

1. The method of correcting the twist of off-balance elastic yarn, which consists in winding 15 the off-balance yarn in a package so that the yarn may be pulled endwise from the package as it is unwound therefrom, pulling the yarn endwise from said package, and rotating the package as the yarn is pulled therefrom at a rate to change 20 the twist of the yarn by a plurality of twists for each turn unwound from the package.

2. The method of correcting the twist of off-balance elastic yarn, which consists in winding the off-balance yarn in a package so that the yarn 25 may be pulled endwise from the package as it is unwound therefrom, pulling the yarn endwise from said package, and rotating said package as the yarn is pulled therefrom at a predetermined ratio to the speed at which the yarn is drawn 30 from the package.

3. The method of correcting the twist of off-balanced elastic yarn formed of a rubber core having an inner cover helically wound thereupon in one direction and an outer cover helically 35 wound thereupon in the opposite direction, which consists in winding the off-balanced yarn in a package so that the yarn may be pulled endwise from the package as it is unwound therefrom, pulling the yarn endwise from said package, and rotating said package as the yarn is pulled therefrom at a predetermined ratio to the speed at 40 which the yarn is drawn from the package.
